WATERPROOF RECEPTACLE

Filed July 20, 1928

UNITED STATES PATENT OFFICE

ARTHUR VON FRANKENBERG, OF NEW YORK, N. Y.

WATERPROOF RECEPTACLE

Application filed July 20, 1928. Serial No. 284,093.

This invention relates to waterproof receptacles for cigarettes or other articles, or the like, especially designed for use by bathers or others where it is important that the case should be proof against the entrance of any moisture thereinto, which would damage the cigarettes, matches, facial powders, or cosmetics, or other contents. The receptacle may however have other uses.

10 Among the objects of the invention is the provision of a device of the character described, which will faithfully serve its purpose, be simple in design and operation and economical in construction, including a watertight proof casing, a tight closing means, and leverage for actuating it, so that the casing may be watertight when closed, and means for ejecting the cigarettes or other contents into position to be withdrawn when wanted, 15 said ejecting means operating simultaneously with the opening of the case.

Other objects of this invention will in part be obvious and in part hereinafter pointed out.

20 The invention accordingly consists in the features of construction, combination of elements, and arrangement of parts which will be exemplified in the construction hereinafter described, and of which the scope of application will be indicated in the following claims.

In the accompanying drawing, in which is shown one of the various possible illustrative embodiments of my invention,

Fig. 1 is a front elevation of a waterproof receptacle or case embodying the invention, shown in closed position;

Fig. 2 is a similar front elevation of the case shown open with the cover lifted, the cover-actuating handle reversed, and a group 40 of cigarettes projected outwardly a short distance above their normal inner position so as to be easily withdrawn from the case;

Fig. 3 is a top plan view of the device in the position shown in Fig. 2;

Fig. 4 is a cross-section on the lines 4, 4, of Fig. 6, the case being closed;

Fig. 5 is a cross-section on the line 5, 5, of Fig. 2 on an enlarged scale;

Fig. 6 is a cross-section on the line 6, 6, 50 of Fig. 1 on an enlarged scale; and

Fig. 7 is a detail edge view of certain parts operating with the pivoted handle.

Referring in detail to the drawing, the hollow receptacle or case 1 is usually a solid tight water-proof box-like device, which can be opened only at one end, preferably at 2, where it is provided with a removable but non-detachable cover 3, operated in opening and closing by a pivoted handle and leverage mechanism connecting the handle 60 with the cover. If desired, the case 1 may be provided with a loop 2^a through which a bather's belt may pass.

This case 1 may hold cigarettes or other smoking material, or matches, or cosmetics 65 and other facial preparations, or small change and the usual contents of a purse, or in fact, any of a long list of articles, and may be of any desired shape, and flat of any degree 70 of thickness or thinness to provide a handy case and accommodate therein a suitable number of articles.

The invention as here illustrated is applied to a case 1 for receiving a package of commercial cigarettes 5, wrapped in the usual 75 paper covering, of which A is one side and B the other side, the side B being broken away near the top so that a few of the cigarettes may be removed from the package and replaced by a card of matches 6, whose flap engages the outside of paper covering B as shown in Figures 3, 4, and 5.

This package 5, so enclosed in its original paper wrapper, with match card 6 clasping same, is inserted into an inner holder, composed of two parallel sides 8, 8, and an integral bottom 9 provided with an underneath flat spring 10 riveted centrally thereto by a rivet 11. The sides 8 are parallel to the narrow sides of case 1, and they are not connected by any members except the bottom 9.

This inner holder for the cigarettes or other articles fits inside of an inner frame somewhat similar thereto, having sides 7 and an integral bottom 7^a. The bottom 7^a rests 95 on the bottom of the case 1; and the holder spring 10 rests on said bottom 7^a; while sides 7 are parallel to sides 8. Thus the cigarette holding device has a slight endwise movement within the inner frame, because the 100

sides 8 are adapted to project beyond the edge of open end 2 when the cover 3 is off; but are forced back into flush relation with the edge of opening 2 when the cover is closed. (See 5 Figures 4 and 5.) When the sides 8 are so forced back flush with edge of opening 2, the spring 10 is compressed against the bottom piece 7^a of the inner frame. Hence spring 10 functions to lift the holder and the cigarette package slightly so as to project the 10 ends of the individual cigarettes beyond mount 2 into a position where they can be easily taken hold of and separately extracted when the cover 3 is lifted away from opening 2 for the purpose of affording access to 15 the contents; and the matches may also be projected forward.

While the holding frame is movable, and capable of longitudinal projection and retraction, the inner frame is secured in a relatively stationary position in the outer case 1, with its bottom piece resting on the bottom of case 1, and its sides 7 spaced at 12 a short distance from the narrow sides of case 1, and 20 with the outer ends of sides 7 flush with the edge of opening 2, these said spaces 12 being narrow but wide enough to contain certain levers and other parts used to operate the cover 3. The spaces 12 at the ends nearest 25 cover 3 are filled with tubes or perforated blocks 13 that are rigidly brazed, soldered, or otherwise securely fastened therein with their outer ends flush with edge of opening 2. In the tubular members 13 are placed the sliding headed rods 26, 26, for the purpose hereinafter to appear. Thus the members 13 afford guides for rods 26, and they assist in enabling the outer case 1 and inner frame 7 and 30 7^a to be fixedly combined together in a spaced 35 relation that insures the narrow spaces 12 between their walls.

The rest of the mechanism for opening and closing the cover 3 will now be described. A 40 rectangular handle member, similar to a bail piece and having a handle proper or cross bar 4, which is parallel to cover 3, is provided with integral parallel arms 4^a, 4^a, which lie 45 near and are moved alongside of the sides of case 1. The ends of arms 4^a of this rectangular handle member are rigidly secured to studs 18 by pins 19, said studs being mounted rotatably in the wall of case 1 as shown in 50 Fig. 7.

The handle is adapted when lifted to cause 55 its bar 4 to engage a rabbet or shoulder 3^a on cover 3 when the latter is closed tightly over the casing entrance 2, see Figure 1; and bar 4 is provided with a thumb projection 4^b to enable bar 4 to be more readily disengaged 60 from rabbet 3^a when the parts are interlocked.

Each stud 18 has thereon a washer 20 outside case 1 and between the case and arm 4^a, as shown in Fig. 7. Also inside case 1 each 65 stud has thereon a flat washer and contiguous

thereto a convex washer 30, the latter bearing against the plate or arm 21 secured on the inner end of stud 18. Said washers are preferably used to space the parts to give free and easy movement, but also to associate them 70 tightly enough together to prevent any leakage in the bearings. The plates or arms 21 at points sufficiently far from studs 18 are pivoted to links 22 by pivots 23, and the links 24 are pivoted by suitable pivots 27 to the 75 rods 26, which rods 26 slide in the tubular guides 13 and the links 24 or a portion thereof also enter and operate in tubes 13, see Figures 4 and 6.

Turning now to the cover 3, it will be noted 80 that it is in the form of a hollow box lid and contains at or near the lower edge a flat strip of rubber, gutta-percha, or similar suitable elastic material 14 fitted closely in the cover; next a parallel brass strip 15 soldered or secured at its end to the cover; and next a parallel steel spring strip 16 that rests on a small central hump or fulcrum 17 on the brass member 15, on which hump 17 as a bearing the spring 16 is flexed at each end when the cover 85 is tightly closed. For the cover 3 and the inner members just mentioned are wholly under the control of the handle 4 and the levers and links and other parts that connect the handle with these devices. The immediate connection of the two systems of levers and links on the two sides of the case is made by the rods 26 which pass through holes in the strips or pieces 14, 15, and 16, near the 90 opposite ends of these strips, see Figure 4, and carry at their ends the heads 28 which lie within the cover contiguous to spring 16, on which they bear more or less tightly when the box is open, but bear strongly when the 95 levers close the cover and thus bend the spring near each end so that the rubber strip 14 may be forced securely and tightly against the edge of the opening 2 all around and thus insure an absolutely watertight and impermeable joint between the closed cover and 100 the box.

The rubber member 14 fits closely within the cover 3 at all times so that it may snugly grip the cover and keep the parts in right relation, and when the cover is closed the rubber piece 14 seats itself very snugly on the edge of the case 1 at opening 2, the ends of the tubular inserts 13 and on the adjoining 105 ends of the parts 7 of the inner frame, while the edge of cover 3 slightly overlaps the end of case 1 like any ordinary thin box lid to assist in further making the joint absolutely tight. The face of rubber member 14 is also provided with a rectangular metallic plate 29 held thereon by screws, pins, or other attaching means, which pass through rubber 110 14 and brass piece 15, see Figure 4. This plate 29 is of a rectangular shape and of precisely the size to fit between the ends of frame 125 7, 7, and the sides of case 1, but opposite to 130

the ends 8, 8, of the movable holder. Thus when the cover closes the plate 29 strikes against the outwardly projecting ends 8, 8, and forces the movable holder and elements carried thereby back into the case, and at the same time the plate 29 fits down between the ends of frame sides 7, 7. This position of plate 29 causes it to serve as a stay or support to keep the sides or ends of the case 1 from buckling or bending inwardly in the event of any undue pressure at these points which might otherwise disturb the correct relations of these parts. The position of these members when the cover is open is very clearly indicated in Fig. 5.

If handle 4 is in the position shown in Figures 1 and 4, with the cover closed, and it is then disengaged from the rabbet 3^a where it serves to lock the cover closed, and is turned down into the position that it and connected parts take in Figures 2 and 5, the result will be to cause the two lines of interpivoted links and levers 21, 22, 24, and 26 to extend themselves vertically and longitudinally, the rods 25 26 rising through the tubular bearings 13 and carrying cover 3 and parts 14, 15, and 16 with them, until the pivots 27 arrive at a point immediately above the bearings 13. When this happens, there will be nothing to hold up the rods 26 as they will be entirely out of bearings 13, and so the weight of cover 3 and parts inside will cause the latter to fall over back on one side or the other as shown in Figure 5, where the cover is on one side out of the way, and the case is open with free access to its contents. The release at this time of the effect of plate 29 on the ends of the holder combined with the expansion of the holder spring 10 lifts the holder 40 and its cigarettes outwardly into a convenient accessible position, the sides 8 extending outwardly beyond the edge of opening 2.

The reverse operation is readily understood. As soon as the needed portion of the 45 contents of the case are taken out of the open case, the user, especially if he be a bather, will wish to instantaneously close the case. The device lends its aid immediately to such a quick closing, for the only act required is 50 to lift the handle 4 back into the position shown in Figure 1; and in so doing the series of links and levers spring into action as before, first bringing the cover 3 forward over the end 2 by straightening up the headed rods 55 and causing them to enter and travel through the tubular bearings 13; then as the handle 4 continues to be lifted the lines of links and levers draw the cover 3 down and tightly over the end of the case, the headed rods bend 60 the steel spring on the hump, the cigarettes retreat into the case as their holder is forced back by the strain of plate 29 on their exposed side end 8, and the rubber pad is sealed closely all around and against the end of the 65 case; while plate 29 fits down in the confining

edges of the inner frame and the sides of the case to brace and sustain as I have explained; all operating to produce a successful waterproof closure. I have referred to the box-lid 3 as the cover, but as a part of the same 70 we must recognize always the several strips which make up the clamping seal and which are also part of the covering means and are connected to the lid particularly by the soldering of the brass plate 15 inside lid 3, but 75 it will be understood that so long as the waterproof sealing remains effective, the lid 3 may be greatly modified or dispensed with, and the several other features inside lid 3 may be modified and changed as may be approved 80 in actual practice. I reserve also the right to make many other changes in the parts within the scope of the ensuing claims.

Having thus described my invention I claim as new and desire to secure by Letters 85 Patent:—

1. In an article of the class described, the combination with a case having an opening at one end, of waterproof closing means therefor including plural clamping members, 90 a cover enclosing same, an operating handle, and interpivoted members connecting the handle with the clamping members.

2. In an article of the class described, the combination with a case having an end opening, of waterproof closing means therefor including a cover, a rubber pad therein, a clamping spring, an operating handle, rods 95 engaging the spring, and means for reciprocating said rod, said means being actuated by the operating handle.

3. In an article of the class described, the combination with a case having an end opening, of waterproof closing means therefor, 100 including a cover, a rubber pad fitting closely within the edge of the same, a metallic plate secured within the cover adjoining the rubber pad and having a hump, a clamping spring which bends over the hump, an external handle, and means connected therewith and actuated thereby for engaging and bending the spring and opening and closing the cover.

4. In an article of the class described, the combination with a case having an end opening, of a cover, a rubber pad therein, a metal support in the cover for the pad, a spring fulcrumed on said support, an external handle and leverage means connecting the handle 110 with the spring in the cover and operable to tightly clamp the cover over the case opening.

5. In an article of the class described, the combination with a case having an opening, 120 of a watertight cover for said opening, an external rectangular pivoted handle, two series of links and levers operated by the handle to open and close the cover, and a movable holder in the case for supporting the 125 contents of the case.

6. In an article of the class described, the combination with a case having an opening, of a waterproof cover for said opening, an externally pivoted handle, two series of links and levers connected with and operated by the handle to open and close the cover, a movable holder in the case having a spring, and an inner frame embracing the holder and secured in a spaced relation to the case.
- 10 7. In an article of the class described, the combination with a case having an opening, of a waterproof cover for said opening, an elastic cushion in said cover, a spring bearing on the cushion, a rectangular external pivoted handle having a cross piece engaging the cover when closed and side pieces integral with the cross piece, studs in the wall of the case to which studs the side pieces of the handle are secured, and interior series 15 of interpivoted links connecting the studs with the cover spring so that the handle may open and close the cover.
- 20 8. In an article of the class described, the combination with a case having an opening, 25 a cover for said opening, an inner frame secured to the case and spaced therefrom, a spring actuated holder within the inner frame and carrying the contents of the case, an external handle for the cover, and means 30 within the case connecting the handle with the cover to open and close said cover.

In testimony whereof I affix my signature,
ARTHUR von FRANKENBERG.
